UNITED STATES PATENT OFFICE.

PAUL RIBBE, OF HALENSEE, NEAR BERLIN, GERMANY, ASSIGNOR TO FERN-SCHNELL-SCHREIBER GES. M. B. H., OF BERLIN, GERMANY.

POLARIZED RELAY.

No. 918,199.

Specification of Letters Patent.

Patented April 13, 1909.

Application filed January 28, 1909. Serial No. 474,809.

To all whom it may concern:

Be it known that I, PAUL RIBBE, a citizen of the Empire of Germany, residing at Halensee, near Berlin, in the Empire of Germany, have invented a new and useful Polarized Relay, of which the following is a specification.

My invention relates to a polarized relay which can be operated by currents or impulses of a very low pressure, such as from 10^{-5} amperes to 10^{-10} amperes and even less. It may be arranged either to momentarily close a secondary circuit or to control effects of light. As many consecutive impulses as from one hundred to several thousand per second can be permitted to circulate in the primary circuit for causing the polarized relay to produce a corresponding number of secondary effects per second. The polarized relay comprises two opposite electromagnetic devices and one common armature, which latter is carried by a strong and short leaf spring and is thereby forced into its normal position, while it is exposed to the differential action of the two electromagnetic devices inserted in a primary circuit. The two electromagnetic devices are arranged to normally both expel the armature for forcing it into its normal position, so that they can be moved together and leave an extremely small space between each of them and the armature. The slightest alterations in the intensity of the fields will then cause the armature to move in one or the other direction without its motion permitting one field to entirely overbalance the other one, so that the armature is prevented from striking the respective poles. The said short and powerful leaf spring is to be without any strain (in the mechanical sense) when the armature is exactly in the neutral zone of the two fields. In this condition even the most powerful spring must necessarily possess a certain elasticity, which with a short length and a strong cross section of the leaf spring permits only an exceedingly small deflection beyond which it offers so great a resistance as to counterbalance the overbalance of the respective field and to prevent the armature from flying. Under these circumstances the stroke of the armature will be so very slight, that no practical use could be made of it, however, its motions in consequence of the three forces offered by the two electromagnetic devices

and by the leaf spring will be very energetic. I therefore employ a lever transmission for multiplying the stroke of the armature and thus utilizing it. As a lever transmission necessarily involves fulcrums and the exceedingly small deflection of the leaf spring and consequently the very insignificant stroke of the armature forbids the use of points or ordinary bearings which would otherwise nearly take up all the movement, I employ very weak leaf springs as fulcrums for a multiplying lever, which latter I connect by means of a small leaf spring with the upper end of a vertical rod rigidly connected with the armature.

In case the polarized relay is to mechanically close and open a secondary circuit, I employ a new contact device. As, however, with the extremely low strength of the current the metallic contacts, such as for example platinum on platinum, are apt to "cleave" to one another and to consume a high percentage of the movement of the contact piece, in case a good and energetic contact is to be procured, such metallic contacts would be useless, since the turn of the above mentioned multiplying lever is but small in spite of the multiplication. I therefore employ in my new contact device mercury for the stationary contact and a platinum needle for the movable contact. In opposition to known contact devices of a similar description I so arrange the platinum needle on the multiplying lever that it does not dip into mercury as usual but only momentarily touches the surface of a small semi-globe of mercury projecting from a vessel. The semi-globe of mercury owing to its small mass can be placed in an opening of a vertical wall, so that the advantage is thereby obtained, that the multiplying lever can be disposed vertically and consequently its center of gravity can be placed in the vertical passing through its fulcrum, which means, that the momentum of the dead masses of all the moved parts is reduced to a minimum.

I will now proceed to describe my invention with reference to the accompanying drawings, in which—

Figure 1 is a vertical longitudinal section through the polarized relay on the line A—B in Figs. 2 and 4, a part on the right being shown in elevation, Fig. 2 is a vertical cross section through the same on the line C—D in Fig. 1, Fig. 3 is a horizontal section through

the same on the broken line E—F in Fig. 2, Fig. 4 is a side view of the same, when looked at from right in Fig. 1, Fig. 5 is a vertical cross section through the line G—H in Fig. 1, 5 the permanent horseshoe magnet being removed, Fig. 6 is a vertical section through the line I—J in Fig. 1 and shows a bracket, Fig. 7 is a part out of Fig. 2, from which the multiplying lever is omitted, Fig. 8 is a horizontal section through the line K—L in Fig. 10 7, Fig. 9 is a vertical section through the line M—N in Fig. 1, the mercury vessel being shown in elevation, Fig. 10 is a side view of a bracket near the mercury vessel, when looked 15 at from right in Fig. 1, Fig. 11 is a part out of Fig. 1 and shows the supporting leaf spring, the armature and the lever transmission, the platinum needle being omitted from the upper end of the multiplying lever, Fig. 20 12 is a side view of the same and is a part out of Fig. 2, Fig. 13 is a part out of Fig. 12 on an enlarged scale and shows the multiplying lever, Fig. 14 is a part out of Fig. 11 on the same enlarged scale, Fig. 15 is a plan view of 25 the same, Fig. 16 is a detail, which will be referred to later on, and Fig. 17 shows on a magnified scale the platinum needle and the semi-globe of mercury.

Similar characters of reference refer to 30 similar parts throughout the several views.

On a suitable base plate 1 are fastened in the same vertical central plane two opposite beds 2, 2' (Fig. 5), on which two carriages 3, 3' are in any known manner longitudinally 35 guided, while they can be adjusted by means of two small hand-wheels 4, 4' rigidly connected with two screw-spindles 5, 5', that are mounted to turn in two brackets 6, 6' and engage in lugs 7, 7' on the carriages 3, 3'. 40 Fig. 6 shows one bracket 6, which is fastened on the bed 2 in a manner clearly shown at Fig. 1. The carriages 3, 3' are each made in one with a projection 8 or 8' and serve for supporting two opposite permanent lamellar 45 horseshoe magnets 9, 9', which are secured on them by means of cross pieces 10, 10' and screws 11, 11'. The horseshoe magnets 9, 9' are provided with polar pieces 12, 13, 12', 13', on which four coils 14, 15, 14', 15' are placed. 50 The base plate 1 carries an insulating piece 16, on which four conductors 17, 18, 17', 18' with binding posts 19, 20, 19', 20', 21, 22, 21', 22' are secured. The four coils 14, 15, 14', 15' are to be connected in series with one 55 another and are shown as connected with the binding posts 19 and 19'.

On the bottom side of the base plate 1 is fastened and insulated therefrom a disk 23, in which the shank 24 of a vise 25 is vertically 60 guided and can be adjusted by means of a screw 26, the head of which is accessible to a screw-driver through a hole 27 and a recess 28 provided in the base plate. The vise 25 serves for supporting a strong vertical leaf 65 spring 29, which can be vertically adjusted

in it by means of screws 30, 30. A rectangular frame 31 (Figs. 11 and 12) of brass or the like is provided, the broad bottom section 32 of which has a slit 33 extending over nearly the whole inside width of the frame 31. The 70 upper end of the leaf spring 29 nicely fits into this slit 33 and can be secured in the frame 31 by means of screws 34, 34. The frame 31 is adapted to receive the armature 35 for the two horseshoe magnets 9, 9', which armature 75 is shown as consisting of a number of superposed plates of soft iron, which can be secured in the frame 31 by means of screws 36, 36. The frame 31 carries a vertical rod 37 of brass or the like screwed into it and 80 having a square head 37' between the ends.

On the base plate 1 is fastened and insulated therefrom a standard 38, which is provided about at half its height with two arms 39, 39' and above them with two vertical 85 guides 40, 40' (Figs. 7 and 8). The two arms 39, 39' carry two adjusting screws 41, 41', which can be regulated by means of small wheels 42, 42' and serve for limiting the movement of the rod 37 by striking its head 90 37'. The left guide 40' in Figs. 1 and 8 serves for guiding a slide 43, which can be vertically adjusted by means of two screws 44, 44 engaging in a slot 45 in it. The slide 43 has an arm 46 (Fig. 7), the upper surface 95 of which forms a guide for the lower part of a vise 47, so as to prevent it from turning, it being fastened by a screw 48. The vise 47 serves for holding fast two very narrow and weak leaf springs 49, 49 which are to carry 100 a very light multiplying lever constructed as follows. The long upper arm 50 may be made from two aluminium strips, which are connected together by rivets or the like (Figs. 13 to 15) and are near their lower ends 105 sharply bent, so that their opposite horizontal projections 50' form the foot of the arm 50, that can be placed on the free ends of the two narrow and weak leaf springs 49, 49. A piece of thin sheet brass or the like 110 is bent in three parallel lines so as to form in its lower part the lower arm 51 of the multiplying lever 50, 51, while the upper part 52 of this piece presents a horizontal recess, into which the two horizontal projections 50' of the arm 50 and the two leaf springs 49, 49 can snugly engage. Of course the said piece requires to be provided with a slot 53 (Fig. 16) before it is bent, so as to permit the arm 50 to engage in this slot 53, after which the 115 parts 49, 49, 50 and 51 are rigidly connected together by rivets or otherwise. A narrow and weak leaf spring 54 is at its one end bent at right angles and is fastened on the lower arm 51 in its middle by soldering or otherwise. The upper end of the above mentioned rod 37 is screw-threaded and a bent arm 55 is put over it and can be vertically 120 adjusted by two nuts 56, 56. The free end of the weak leaf spring 54 is placed on the 125 130

free end of the arm 55 and is thereon fastened by means of a plate 57 and two screws 58, 58 (Fig. 8). I have indicated in Fig. 14 the leaf spring 54 by two parallel lines for the sake of clearness, while in reality it is made quite thin, perhaps as thin as two tenths of a millimeter, while its width may be perhaps half a millimeter. The two leaf springs 49, 49 may be made of the same strength as the leaf spring 54. However I do not bind myself to these measures, as they will have to depend upon the circumstances.

In case the polarized relay described so far is to serve for closing and opening a secondary circuit, the upper arm 50 may be made from a single aluminium strip doubled by bending and adapted to receive in its doubled end a platinum needle 59 (Fig. 17), which is fastened on it in any known manner.

The right guide 40 in Figs. 1 and 8 serves for guiding a slide 60 (Fig. 9), which can be vertically adjusted by a screw 61 engaging in a slot 62 in it. The slide 60 has a horizontal arm 63, the upper surface of which forms a guide for a plate 64 so as to prevent it from turning, it being fastened by a screw 65. Fastened on the plate 64 and insulated therefrom is a bearing 66 for a turnable mercury vessel 67, which is adapted to turn on a horizontal pin 68 fastened in the bearing 66. It is made conductive. From Fig. 1 it will be seen, that the mercury vessel 67 can rock in the longitudinal central plane of the relay, in which plane also the multiplying lever 50, 51 is to rock. For adjusting the mercury vessel 67 an adjusting screw 69 is employed, which engages in a vertical bracket 71 (Fig. 10) made in one with the bearing 66 and is provided with a small wheel 70 by means of which it can be regulated. The bracket 71 has a slot 72 in which a vertical leaf spring 73 engages, it being fastened with its lower end on the bearing 66 and engaging with its upper end in a slot in a stud 74 fastened on the mercury vessel 67. The spring 73 serves for pressing the mercury vessel 67 to the right in Fig. 1 and the adjusting screw 69 is adapted to bear on the said vessel. This vessel 67 is provided with a horizontal nozzle 75 and a nut 76, both of them being preferably screwed into it. A screw 77 engages in the nut 76 and is provided with a small wheel 78 by means of which it can be regulated. The nozzle 75 has a very fine bore, say one of half a millimeter diameter. The vessel 67 is to be completely filled up with mercury and the screw 77 is by its wheel 78 so turned as to force the mercury so much out of the vessel 67, that a semi-globe 86 of mercury just projects from the outer end of the nozzle 75 (Fig. 17). By regulating the adjusting screw 77 a stronger or weaker curvature can be given to the semi-globe 86 of mercury. The bracket 71 is provided with a binding post

79, which is shown as connected with the binding post 20 by an insulated conductor 80 (Fig. 4). The standard 38 is provided with a binding post 81 (Fig. 2), which is shown as connected with the binding post 70 20' by an insulated conductor 82.

The standard 38 is provided at its upper end with a horizontal cross hole 83 and with two screws 84, 84, which serve for fastening an optical device of any known construction. For example a part of this device may be introduced into the hole 83 and a beam of rays of light may be sent forward through its lens 85 (Fig. 12) and the focus may be normally in the center of the rounding at the upper end of the arm 50, as is indicated by the dotted lines in Fig. 12. Besides the lens 85 in Fig. 12 I have not shown the optical device, as it is immaterial to my invention.

The polarized relay operates as follows: The two permanent horseshoe magnets 9 and 9' are in a known manner so arranged as to both repel the armature 35 and force it into its normal vertical position between them, as is shown at Figs. 1 and 3. This permits the two horseshoe magnets 9, 9' to be moved together so near the armature 35, as to leave but a very slight space (for example half a millimeter) between the armature 35 and the polar pieces 12, 13 and 12', 13'. The four coils 15, 14, 14', 15', connected with the respective primary circuit of any kind by means of the two outer binding posts 21 and 21', are in a known manner so wound, as to enable them to produce a differential action upon the armature 35, when impulses circulate in the primary circuit, so that the armature can be moved in either direction. The vise 25 is vertically so adjusted for lengthening or shortening the free length of the leaf spring 29 as to enable the latter to exert a sufficient pressure for preventing the armature 35 from striking and bearing on the respective polar pieces when attracted. The two adjusting screws 41, 41' are by means of their wheels 42, 42' adjusted for limiting the movement of the rod 37 as may be desired. The leaf spring 54 serves for pushing the lower arm 51 forward in one direction or for pulling it in the other direction on the armature 35 being attracted in the respective direction. The spring 54 may slightly bend during its movement. Normally it is to hold in combination with the two small leaf springs 49, 49 the upper arm 50 of the multiplying lever 50, 51 in a perfectly vertical position, so as to reduce the momentum of its mass during the motion to a minimum. The two leaf springs 49, 49 carrying the multiplying lever 50, 51 render it possible to transfer the extremely small movement of the rod 37 and the arm 55 to the upper end of the arm 50 without any loss while at the same time multiplying it, so that the upper end can

make a movement through a distance of say from one to two millimeters or thereabout. The several parts of the lever transmission from the supporting leaf spring 29 upward to the multiplying lever should be so made, that the arm 50 is rocked once only for every impulse circulating in the primary circuit. When the relay is wanted for closing and opening a secondary circuit, the mercury vessel 67 with the parts therewith connected will have to be put on, while the upper arm 50 of the multiplying lever 50, 51 requires to have the platinum needle 59. These parts will then be connected with the respective secondary circuit of any kind by the two outer binding posts 22 and 22'. Each time when an impulse circulates in the primary circuit the upper arm 50 will make one movement in the respective direction, so that its platinum needle can momentarily touch the surface of the semi-globe 86 of mercury for closing the secondary circuit. This polarized relay proves to be exceedingly sensitive, so that very many consecutive impulses, say from one hundred to several thousand and more per second, can circulate in the primary circuit for producing as many impulses in the secondary circuit. It is essential to make the parts of the lever transmission very light and to reduce the momentum of their moving masses to a minimum for rendering the relay capable of operating rapidly. For this reason the semi-globe 86 of mercury projecting from a horizontal nozzle is very useful in combination with the vertical multiplying lever 50, 51. The exceedingly small stroke of the armature 35 enables it to reciprocate most rapidly in response to the rapidly following impulses in the primary circuit.

When the relay is wanted for controlling rays of light with the aid of optical devices, movable mirrors etc., the mercury vessel 67 and the parts therewith connected need not be employed, while the platinum needle 59 on the arm 50 is dispensed with, as is shown at Figs. 13 and 14. Then during the operation of the polarized relay the upper end of the arm 50 will momentarily permit the rays of light passing from some source through the hole 83 to pass on once for every impulse in the primary circuit.

The polarized relay described can be varied in many respects without departing from the spirit of my invention, and I expressly desire it to be understood, that I do not bind myself to the details of the construction shown and described. The two opposite permanent horseshoe magnets and the four coils may be replaced by two opposite electromagnets of any known construction producing a similar differential action upon the armature. Where so preferred, the arm 55 may be omitted and the leaf spring 54 may be connected direct with the upper end

of the rod 37 in any known manner, in which case the vertical multiplying lever 50, 51 requires to be shifted to the left in Fig. 1, so that the axis of the rod 37 passes through the screw 58 (Fig. 14) or its equivalent. 70

I claim:

1. In a polarized relay of the class described, the combination with a frame, of a leaf spring secured in said frame, an armature carried by said leaf spring and thereby forced into its normal position, two opposite electromagnetic devices carried by said frame and adapted to be inserted in a circuit for producing a differential action on said armature, a rod connected with said armature and partaking in its movement, a multiplying lever, leaf springs secured at one end in said frame and rigidly connected at the other end with said multiplying lever while serving as its fulcrum, and a leaf spring connecting said multiplying lever with the free end of said rod, the free end of said multiplying lever being adapted on being moved to close a secondary circuit. 75

2. In a polarized relay of the class described, the combination with a frame, of a vertical leaf spring secured in said frame, an armature carried by said vertical leaf spring and thereby forced into its normal position, two opposite electromagnetic devices carried by said frame and adapted to be inserted in a circuit for producing a differential action on said armature, a vertical rod connected with said armature and partaking in its movement, a vertical multiplying lever, horizontal leaf springs secured at one end in said frame and rigidly connected at the other end with said vertical multiplying lever while serving as its fulcrum, and a horizontal leaf spring connecting said multiplying lever with the free end of said vertical rod, the free end of said multiplying lever being adapted on being moved to close a secondary circuit. 80

3. In a polarized relay of the class described, the combination with a frame, of a vertical leaf spring secured with its lower end in said frame, an armature supported by said vertical leaf spring and thereby forced into its normal position, two opposite electromagnetic devices carried by said frame and adapted to be inserted in a circuit for producing a differential action on said armature, a vertical rod supported by said armature and partaking in its movement, a vertical multiplying lever, horizontal leaf springs secured at one end in said frame and rigidly connected at the other end with said vertical multiplying lever while serving as its fulcrum, and a horizontal leaf spring connecting said multiplying lever with the free end of said vertical rod, the free end of said multiplying lever being adapted on being moved to close a secondary circuit. 85

4. In a polarized relay of the class de- 130

- scribed, the combination with a frame, of a vertical leaf spring secured in said frame and insulated therefrom, an armature carried by said vertical leaf spring and thereby forced 5 into its normal position, two opposite electromagnetic devices carried by said frame and adapted to be inserted in a primary circuit for producing a differential action on said armature, a vertical rod connected with said armature and partaking in its movement, an insulated part fastened on said frame, a vertical multiplying lever provided at its free end with a platinum needle, horizontal leaf springs secured at one end in said 10 insulated part and rigidly connected at the other end with said vertical multiplying lever while serving as its fulcrum, a horizontal leaf spring connecting said multiplying lever with the free end of said vertical rod, a closed conductive vessel on said insulated part and insulated therefrom and adapted to be filled up with mercury, a horizontal nozzle with a fine bore on said conductive vessel in line with said platinum needle, and a regulating screw 15 engaging in said conductive vessel and adapted to cause a fine semi-globe of mercury to project from the end of said horizontal nozzle while adjusting the curvature of this semi-globe, said insulated part and said conductive vessel being adapted to be inserted in a secondary circuit, and said multiplying lever being adapted on being moved to momentarily close the secondary circuit by its platinum needle touching the semi-globe of mercury. 20
5. In a polarized relay of the class described, the combination with a frame, of a vertical leaf spring secured with its lower end in said frame and insulated therefrom, an armature supported by said vertical leaf spring and thereby forced into its normal position, two opposite electromagnetic devices carried by said frame and adapted to be inserted in a primary circuit for producing a differential action on said armature, a vertical rod supported by said armature and partaking in its movement, an insulated part fastened on said frame, a vertical multiplying lever provided at its upper free end with a platinum needle, horizontal leaf springs secured at one end in said insulated part and rigidly connected at the other end with said vertical multiplying lever while serving as its fulcrum, a horizontal leaf spring connecting said multiplying lever with the upper free end of said vertical rod, a closed conductive vessel on said insulated part and insulated therefrom and adapted to be filled up with mercury, a horizontal nozzle with a fine bore 25 on said conductive vessel in line with said platinum needle, and a regulating screw engaging in said conductive vessel and adapted to cause a fine semi-globe of mercury to project from the end of said horizontal nozzle while adjusting the curvature of this semi-globe. 30
6. In a polarized relay of the class described, the combination with a frame, of a leaf spring adjustably secured in said frame, an armature carried by said leaf spring and thereby forced into its normal position, two opposite electromagnetic devices adjustable on said frame and adapted to be inserted in a circuit for producing a differential action on said armature, a rod connected with said armature and partaking in its movement, means for adjusting the turn of said rod, a multiplying lever, leaf springs secured at one end in said frame and rigidly connected at the other end with said multiplying lever while serving as its fulcrum, and a leaf spring connecting said multiplying lever with the free end of said rod, the free end of said multiplying lever being adapted on being moved to close a secondary circuit. 35
7. In a polarized relay of the class described, the combination with a frame, of a vertical leaf spring adjustably secured in said frame, an armature carried by said vertical leaf spring and thereby forced into its normal position, two opposite electromagnetic devices adjustable on said frame and adapted to be inserted in a circuit for producing a differential action on said armature, a vertical rod connected with said armature and partaking in its movement, means for adjusting the turn of said rod, a vertical multiplying lever, horizontal leaf springs secured at one end in said frame and rigidly connected at the other end with said vertical multiplying lever while serving as its fulcrum, and a horizontal leaf spring connecting said multiplying lever with the free end of said vertical rod, the free end of said multiplying lever being adapted on being moved to close a secondary circuit. 40
8. In a polarized relay of the class described, the combination with a frame, of a vertical leaf spring adjustably secured with its lower end in said frame, an armature supported by said vertical leaf spring and thereby forced into its normal position, two opposite electromagnetic devices adjustable on said frame and adapted to be inserted in a circuit for producing a differential action on said armature, a vertical rod supported by said armature and partaking in its movement, means for adjusting the turn of said vertical rod, a vertical multiplying lever, horizontal leaf springs secured at one end in said frame and rigidly connected at the other end with said vertical multiplying lever while serving as its fulcrum, and a horizontal leaf spring connecting said multiplying lever with the free end of said vertical rod, the free end of said multiplying lever being adapted on being moved to close a secondary circuit. 45
9. In a polarized relay of the class described, the combination with a frame, of a vertical leaf spring adjustably secured with its lower end in said frame, an armature supported by said vertical leaf spring and thereby forced into its normal position, two opposite electromagnetic devices adjustable on said frame and adapted to be inserted in a circuit for producing a differential action on said armature, a vertical rod supported by said armature and partaking in its movement, means for adjusting the turn of said vertical rod, a vertical multiplying lever, horizontal leaf springs secured at one end in said frame and rigidly connected at the other end with said vertical multiplying lever while serving as its fulcrum, and a horizontal leaf spring connecting said multiplying lever with the free end of said vertical rod, the free end of said multiplying lever being adapted on being moved to close a secondary circuit. 50
10. In a polarized relay of the class described, the combination with a frame, of a vertical leaf spring adjustably secured with its lower end in said frame, an armature supported by said vertical leaf spring and thereby forced into its normal position, two opposite electromagnetic devices adjustable on said frame and adapted to be inserted in a circuit for producing a differential action on said armature, a vertical rod supported by said armature and partaking in its movement, means for adjusting the turn of said vertical rod, a vertical multiplying lever, horizontal leaf springs secured at one end in said frame and rigidly connected at the other end with said vertical multiplying lever while serving as its fulcrum, and a horizontal leaf spring connecting said multiplying lever with the free end of said vertical rod, the free end of said multiplying lever being adapted on being moved to close a secondary circuit. 55
11. In a polarized relay of the class described, the combination with a frame, of a vertical leaf spring adjustably secured with its lower end in said frame, an armature supported by said vertical leaf spring and thereby forced into its normal position, two opposite electromagnetic devices adjustable on said frame and adapted to be inserted in a circuit for producing a differential action on said armature, a vertical rod supported by said armature and partaking in its movement, means for adjusting the turn of said vertical rod, a vertical multiplying lever, horizontal leaf springs secured at one end in said frame and rigidly connected at the other end with said vertical multiplying lever while serving as its fulcrum, and a horizontal leaf spring connecting said multiplying lever with the free end of said vertical rod, the free end of said multiplying lever being adapted on being moved to close a secondary circuit. 60
12. In a polarized relay of the class described, the combination with a frame, of a vertical leaf spring adjustably secured with its lower end in said frame, an armature supported by said vertical leaf spring and thereby forced into its normal position, two opposite electromagnetic devices adjustable on said frame and adapted to be inserted in a circuit for producing a differential action on said armature, a vertical rod supported by said armature and partaking in its movement, means for adjusting the turn of said vertical rod, a vertical multiplying lever, horizontal leaf springs secured at one end in said frame and rigidly connected at the other end with said vertical multiplying lever while serving as its fulcrum, and a horizontal leaf spring connecting said multiplying lever with the free end of said vertical rod, the free end of said multiplying lever being adapted on being moved to close a secondary circuit. 65

with the free end of said vertical rod, the free end of said multiplying lever being adapted on being moved to close a secondary circuit.

- 5   9. In a polarized relay of the class de-
scribed, the combination with a frame, of a
vertical leaf spring adjustably secured in said
frame and insulated therefrom, an armature
carried by said vertical leaf spring and
10   thereby forced into its normal position, two
opposite electromagnetic devices adjustable
on said frame and adapted to be inserted in a
primary circuit for producing a differential
15   action on said armature, a vertical rod con-
nected with said armature and partaking in
its movement, an insulated part fastened on
said frame, means on said insulated part for
adjusting the turn of said vertical rod, a ver-
20   tical multiplying lever provided at its free
end with a platinum needle, horizontal leaf
springs secured at one end in said insulated
part and rigidly connected at the other end
with said vertical multiplying lever while
serving as its fulcrum, a horizontal leaf spring
25   connecting said multiplying lever with the
free end of said vertical rod, a closed conductive
vessel adjustable on said insulated part
and insulated therefrom and adapted to be
filled up with mercury, a horizontal nozzle
30   with a fine bore on said conductive vessel in
line with said platinum needle, and a regu-
lating screw engaging in said conductive ves-
sel and adapted to cause a fine semi-globe of
35   mercury to project from the end of said hori-
zontal nozzle while adjusting the curvature
of this semi-globe, said insulated part and
said conductive vessel being adapted to be
inserted in a secondary circuit, and said mul-
tiplying lever being adapted on being moved
40   to momentarily close the secondary circuit
by its platinum needle touching the semi-
globe of mercury.

10. In a polarized relay of the class described, the combination with a frame, of a vertical leaf spring adjustably secured with its lower end in said frame and insulated therefrom, an armature supported by said vertical leaf spring and thereby forced into its normal position, two opposite electro-
50 magnetic devices adjustable on said frame and adapted to be inserted in a primary circuit for producing a differential action on said armature, a vertical rod supported by said armature and partaking in its move-
55 ment, an insulated part fastened on said frame, means on said insulated part for adjusting the turn of said vertical rod, a vertical multiplying lever provided at its upper free end with a platinum needle,
60 horizontal leaf springs secured at one end in said insulated part and rigidly connected at the other end with said vertical multiplying lever while serving as its fulcrum, a horizontal leaf spring connecting
65 said multiplying lever with the free end of

said vertical rod, a closed conductive vessel
adjustable on said insulated part and in-
sulated therefrom and adapted to be filled
up with mercury, a horizontal nozzle with a
fine bore on said conductive vessel in line 70
with said platinum needle, and a regulating
screw engaging in said conductive vessel and
adapted to cause a fine semi-globe of mer-
cury to project from the end of said horizontal
nozzle while adjusting the curvature of this 75.
semi-globe, said insulated part and said con-
ductive vessel being adapted to be inserted
in a secondary circuit, and said multiplying
lever being adapted on being moved to mo-
mentarily close the secondary circuit by its 80
platinum needle touching the semi-globe of
mercury.

mercury. 11. In a polarized relay, the combination with a frame, of a closed conductive vessel adjustable on said frame and insulated therefrom and adapted to be filled up with mercury, a horizontal nozzle with a fine bore on said conductive vessel, a regulating screw engaging in said conductive vessel and adapted to cause a fine semi-globe of mercury to project from the end of said horizontal nozzle while adjusting the curvature of this semi-globe, an insulated part fastened on said frame, a lever fulcrumed in said insulated part and carrying a platinum needle adapted to momentarily touch the surface of said semi-globe of mercury, and means adapted to be operated by a primary circuit for reciprocating said lever, said insulated part and said conductive vessel being adapted to be inserted in a secondary circuit. 85 90 95 100

12. In a polarized relay of the class described, the combination with a frame, of a vertical leaf spring secured in said frame, an armature carried by said vertical leaf spring and thereby forced into its normal position, two opposite permanent horseshoe magnets with polar pieces carried by said frame and adapted to both expel said armature for forcing it into its normal position, four coils on the polar pieces of said permanent horseshoe magnets and adapted to be inserted in a circuit for producing a differential action on said armature, a vertical rod connected with said armature and partaking in its movement, a vertical multiplying lever, horizontal leaf springs secured at one end in said frame and rigidly connected at the other end with said vertical multiplying lever while serving as its fulcrum, and a horizontal leaf spring connecting said multiplying lever with the free end of said vertical rod, the free end of said multiplying lever being adapted on being moved to close a secondary circuit. 105 110 115 120

13. In a polarized relay of the class described, the combination with a frame, of a vertical leaf spring secured with its lower end in said frame, an armature supported by said vertical leaf spring and thereby forced into its normal position, two opposite permanent 130

horseshoe magnets with polar pieces carried by said frame and adapted to both expel said armature for forcing it into its normal position, four coils on the polar pieces of said permanent horseshoe magnets and adapted to be inserted in a circuit for producing a differential action on said armature, a vertical rod supported by said armature and partaking in its movement, a vertical multiplying lever, horizontal leaf springs secured at one end in said frame and rigidly connected at the other end with said vertical multiplying lever while serving as its fulcrum, and a horizontal leaf spring connecting said multiplying lever with the free end of said vertical rod, the free end of said multiplying lever being adapted on being moved to close a secondary circuit.

14. In a polarized relay of the class described, the combination with a frame, of a vertical leaf spring secured in said frame and insulated therefrom, an armature carried by said vertical leaf spring and thereby forced into its normal position, two opposite permanent horseshoe magnets with polar pieces carried by said frame and adapted to both expel said armature for forcing it into its normal position, four coils on the polar pieces of said permanent horseshoe magnets and adapted to be inserted in a primary circuit for producing a differential action on said armature, a vertical rod connected with said armature and partaking in its movement, an insulated part fastened on said frame, a vertical multiplying lever provided at its free end with a platinum needle, horizontal leaf springs secured at one end in said insulated part and rigidly connected at the other end with said vertical multiplying lever while serving as its fulcrum, a horizontal leaf spring connecting said multiplying lever with the free end of said vertical rod, a closed conductive vessel on said insulated part and insulated therefrom and adapted to be filled up with mercury, a horizontal nozzle with a fine bore on said conductive vessel in line with said platinum needle, and a regulating screw engaging in said conductive vessel and adapted to cause a fine semi-globe of mercury to project from the end of said horizontal nozzle while adjusting the curvature of this semi-globe, said insulated part and said conductive vessel being adapted to be inserted in a secondary circuit, and said multiplying lever being adapted on being moved to momentarily close the secondary circuit by its platinum needle touching the semi-globe of mercury.

15. In a polarized relay of the class described, the combination with a frame, of a vertical leaf spring adjustably secured in said frame, an armature carried by said vertical leaf spring and thereby forced into its normal position, two opposite permanent horseshoe magnets with polar pieces adjustable on said frame and adapted to both expel said armature for forcing it into its normal position, four coils on the polar pieces of said permanent horseshoe magnets and adapted to be inserted in a circuit for producing a differential action on said armature, a vertical rod connected with said armature and partaking in its movement, means for adjusting the turn of said rod, a vertical multiplying lever, horizontal leaf springs secured at one end in said frame and rigidly connected at the other end with said vertical multiplying lever while serving as its fulcrum, and a horizontal leaf spring connecting said multiplying lever with the free end of said vertical rod, the free end of said multiplying lever being adapted on being moved to close a secondary circuit.

16. In a polarized relay of the class described, the combination with a frame, of a vertical leaf spring secured with its lower end in said frame and insulated therefrom, an armature supported by said vertical leaf spring and thereby forced into its normal position, two opposite permanent horseshoe magnets

with polar pieces carried by said frame and adapted to both expel said armature for forcing it into its normal position, four coils on the polar pieces of said permanent horseshoe magnets and adapted to be inserted in a primary circuit for producing a differential action on said armature, a vertical rod supported by said armature and partaking in its movement, an insulated part fastened on said frame, a vertical multiplying lever provided at its upper free end with a platinum needle, horizontal leaf springs secured at one end in said insulated part and rigidly connected at the other end with said vertical multiplying lever while serving as its fulcrum, a horizontal leaf spring connecting said multiplying lever with the upper free end of said vertical rod, a closed conductive vessel on said insulated part and insulated therefrom and adapted to be filled up with mercury, a horizontal nozzle with a fine bore on said conductive vessel in line with said platinum needle, and a regulating screw engaging in said conductive vessel and adapted to cause a fine semi-globe of mercury to project from the end of said horizontal nozzle while adjusting the curvature of this semi-globe, said insulated part and said conductive vessel being adapted to be inserted in a secondary circuit, and said multiplying lever being adapted on being moved to momentarily close the secondary circuit by its platinum needle touching the semi-globe of mercury.

17. In a polarized relay of the class described, the combination with a frame, of a vertical leaf spring adjustably secured with its lower end in said frame, an armature supported by said vertical leaf spring and thereby forced into its normal position, two opposite permanent horseshoe magnets with

125 130

5 polar pieces adjustable on said frame and adapted to both expel said armature for forcing it into its normal position, four coils on the polar pieces of said permanent horseshoe magnets and adapted to be inserted in a circuit for producing a differential action on said armature, a vertical rod supported by said armature and partaking in its movement, means for adjusting the turn of said 10 vertical rod, a vertical multiplying lever, horizontal leaf springs secured at one end in said frame and rigidly connected at the other end with said vertical multiplying lever while serving as its fulcrum, and a horizontal leaf spring connecting said multiplying lever with the free end of said vertical rod, the free end of said multiplying lever being adapted on being moved to close a secondary circuit.

15 18. In a polarized relay of the class described, the combination with a frame, of a vertical leaf spring adjustably secured in said frame and insulated therefrom, an armature carried by said vertical leaf spring and thereby forced into its normal position, two opposite permanent horseshoe magnets with polar pieces adjustable on said frame and adapted to both expel said armature for forcing it into its normal position, four coils on the polar pieces of said permanent horseshoe magnets and adapted to be inserted in a primary circuit for producing a differential action on said armature, a vertical rod connected with said armature and partaking in its movement, an insulated part on said 20 frame, means on said insulated part for adjusting the turn of said vertical rod, a vertical multiplying lever provided at its free end with a platinum needle, horizontal leaf springs secured at one end in said insulated part and rigidly connected at the other end with said vertical multiplying lever while serving as its fulcrum, a horizontal leaf spring connecting said multiplying lever with the upper free end of said vertical rod, a closed conductive vessel adjustable on said insulated part and insulated therefrom and adapted to be filled up with mercury, a horizontal nozzle with a fine bore on said conductive vessel in line with said platinum needle, and a regulating screw engaging in said conductive vessel and adapted to cause a fine semi-globe of mercury to project from the end of said horizontal nozzle while adjusting the curvature of this semi-globe, said insulated part and said conductive vessel being adapted to be inserted in a secondary circuit, and said multiplying lever being adapted on being moved to 25 momentarily close the secondary circuit by its platinum needle touching the semi-globe of mercury.

30 40 45 50

55 said conductive vessel being adapted to be inserted in a secondary circuit, and said multiplying lever being adapted on being moved to momentarily close the secondary circuit by its platinum needle touching the semi-globe of mercury.
